UNITED STATES PATENT OFFICE

JOHN D. POLLARD, OF CHICAGO, ILLINOIS

TRIGGER MECHANISM

Application filed March 31, 1930. Serial No. 440,337.

This invention relates to guns, and more particularly to the trigger mechanism thereof. It has for its principal object to improve upon the trigger mechanism of firearms in general, but is directed more particularly to sporting and trap guns.

In the ordinary gun lock mechanism the hammer is cocked manually, as by a special operating device or breaking the gun at the jointure of the breech and stock, and the hammer is released, after taking aim, by pulling the trigger. In pulling the trigger to release the hammer a flinching frequently occurs, with the result that the poise is disturbed and the gun moved out of aim, which is difficult to overcome except by an expert, and is quite a disadvantage in trapshooting and other sporting uses of the gun.

The present invention has been brought about to overcome the disadvantages of the ordinary trigger mechanism, and consists broadly in the provision of a novel tripping mechanism for the cocked hammer of the gun whereby the trigger is initially pulled by the application of the user's finger prior to aiming the gun and then released, whereby the tripping mechanism is automatically actuated to release the hammer from its cocked condition. The invention further consists in the parts and combinations and arrangements of parts as hereinafter described and set forth in the appended claims.

In the accompanying drawings, illustrating a practical adaptation of the invention,—

Fig. 1 is a fragmentary perspective view, with parts broken away, of a gun in the region of the breech and the firing mechanism;

Fig. 2 is a fragmentary plan view of the trigger mechanism;

Fig. 3 is a view of the trigger mechanism in normal condition when cooperating with the cocked hammer;

Fig. 4 is a view illustrating the action of the trigger element in the first stage of its operation;

Fig. 5 is a view showing the trigger element fully retracted; and

Fig. 6 is a view showing the initial action of the trigger element upon the release of the operator's finger therefrom.

Referring now to the drawings, the numeral 10 designates the breech portion of a gun, and 11 the stock. The gun represented in the drawings is of that type where the breech portion and stock are hingedly connected and normally held in closed condition by a releasable locking mechanism controlled by the usual external lever member 12. In this type of gun the hammer is cocked or set in firing condition by what is known as "breaking" the gun or, in other words, releasing the lock and swinging the barrel with relation to the stock about the axis of the pivotal connection between the breech and the stock. In this operation the cocking cam 13 actuates a rod 14, which in turn engages a cam extension 15 on the hammer member 16, which latter is thereby rocked about its pivotal axis and compresses a spring 17. In the cocked position of the hammer 16 it is set in operable relation to the firing pin 18, in which relation it is held by the sear or latch element 19, whose end portion 20 engages a shoulder 21 on the hammer element near the pivotal axis thereof. This sear or latch element 19 is pivotally mounted, as at 22, and is normally pressed into engagement with the hammer element 16 by a leaf spring 23.

Mounted in cooperative relation to the sear or latch member 19 is a trigger element 24 comprising a flat plate-like body portion which is located in a longitudinal slot 25 in the trigger plate 26 which is usually provided in gun structures of this character. This trigger element 24 is provided with trunnions 27 which rest pivotally and slidably on the trigger plate 26 on opposite sides of the slot 25, and a portion of the trigger element which projects below the plate 26 has a hooked extension or finger engaging portion 28, about which is placed the usual guard loop 29.

The rear portion of the body plate 24 of the trigger element is provided with a seat 30 for the engagement of the end portion of a compression spring 31, whose opposite end portion is inserted in a socket 32 provided therefor in the adjacent body portion of the gun stock; said socket being preferably lined with a metallic bushing 33. This spring 31,

which is constantly under compression, normally holds the trigger element against the forward end of the slot 25 and the portion of the body plate 24 to the rear of the trunnions 27 in contact with the upper face of the trigger plate 26, as shown more clearly in Fig. 3 of the drawings.

The portion of the trigger member forwardly of the trunnions 27 and the portion 10 of the sear 19 rearward of its pivotal axis 22 cooperate in overlapping relation to each other, the sear having a notched portion 34 at its lower edge which affords clearance for a stud 35 on the trigger element 24. In the normal position of the trigger element the stud 35 is located approximately centrally of the notch 34, as shown in Fig. 3, the sear or latch element 19 being in its normal engaging relation with the hammer member 16, whether 20 the hammer element is in cocked condition or not, the only difference being that in its cocked condition its shoulder 21 is engaged with the end 20 of the sear or latch element 19, whereas in the fired condition the hammer 25 element is engaged slidably with said end portion 20 of the sear or latch element adjacent to said shoulder 21. In actuating the trigger element 24 the external hooked portion 28 is pressed by the operator's finger, 30 thereby rocking the trigger member on its trunnions 27 and bringing the forward portion of the trigger element into contact with the trigger plate 26, as shown in Fig. 4, in which position the stud 35 is entirely out of 35 the notch 34 and clear of the lower edge portion of the sear or latch element 19. As soon as the forward portion of the trigger element 24 engages the trigger plate 26 the continued pressure of the operator's finger on the hook portion 28 slides the latch element rearwardly in the same relation to the trigger plate 26 until said trigger element is arrested by the rear end of the slot 25, as shown in Fig. 5. In this position the operator keeps his finger 40 in pressing engagement with the hook 28 until such time as it is desired to release the hammer member 16, provided, of course, said hammer member 16 has been cocked or set in firing position, as shown in Fig. 3, and at 45 this stage the stud 35 is located under the rear portion 36 of the sear or latch element 19. As soon as the hook 28 is relieved of the pressure of the operator's finger the spring 31 rocks the trigger element 24 on the trunnions 27, thereby depressing the rear portion and lifting the forward portion of said trigger element and bringing the stud 35 into contact with said end portion 36 of the sear or latch element 19, whereupon the latter is 50 rocked about its pivotal axis 22 and the end portion 20 thereof is moved out of engagement with the shoulder 21 of the hammer member 16. The hammer member 16 being thus released, it is quickly snapped into engagement with the firing pin 18 by the action 55 60 65 66

of the spring 17 in the same manner as in the ordinary mechanism where the sear is released directly by the pull of the trigger. Instantly after the trigger element 24 has been thus actuated, as shown in Fig. 6, it is moved forwardly by the action of the spring 30 and restored to its normal position, as shown in Fig. 3, the spring 23 restoring the sear or latch element 19 to its normal position with its forward end portion 20 in contact with the hammer member 16, as hereinbefore set forth.

By the provision herein set forth in accordance with the present invention it is obvious that the hammer may be cocked and the gun poised and aimed with the trigger element 24 held retracted, and as the trigger element is actuated by the spring 31 to trip the sear or latch element 19 and restore the latch element to its normal position, as herein set forth, obviously the gun is fired without flinching on the part of the user, which is of material advantage, particularly in trapshooting and other instances where quickness is required in releasing the hammer.

While the construction and arrangement herein shown and described embodies a practical adaptation of the invention, it is understood that the structure may be modified in many respects without in the least departing from the spirit and scope of the invention as defined by the appended claims.

Having thus described my invention, what I claim as new and desire to secure by Letters Patent is:

1. In a gun, a hammer, cocking mechanism and releasable retaining element, a trigger element pivotally and slidably supported in cooperative relation to said releasable retaining element, and a spring acting upon said trigger element to yieldably hold it in normal position and to return it to said position, said trigger element being manually retractile into operable relation with respect to said releasable retaining element and operating to disengage said retaining element from the cocking mechanism during the initial part of the return movement of said trigger element when relieved of retractive pressure thereon.

2. In a gun, a hammer, cocking means, and a sear for retaining the hammer in cocked condition, a trigger element slidably and pivotally mounted in cooperative relation to said sear, a spring acting upon said trigger element to yieldably hold it in normal position and to restore it to such position, said trigger element being retracted by the pressure of the user's finger thereon and rocked out of engaging relation with said sear during such actuation thereof, said trigger element being reversely rocked during the initial part of its spring returned actuation whereby to actuate said sear and release the hammer.

3. In a gun, in combination with the regular cocking means including a releasable hammer retaining element, a spring actuated trigger element pivotally and slidably supported in cooperative relation to said hammer retaining element, said trigger element being initially rocked out of engaging relation to said hammer retaining element during a retractive actuation thereof, and being 5 reversely rocked during the initial part of its return movement to normal position whereby to engage and actuate said hammer retaining element to effect the release of the latter from engagement with the hammer.
- 15 4. In a gun, cocking mechanism including a releasable hammer retaining element, said hammer retaining element being pivotally supported in cooperative relation to the hammer and normally spring-pressed in engagement 20 with the hammer, said hammer retaining element having a recessed under portion, and a trigger element pivotally and slidably supported in cooperative relation to said hammer retaining element, said trigger element 25 having an extension located normally in said recessed portion of the hammer retaining element without engagement therewith but being engageable with a portion of said element adjacent to the recess, and a 30 spring acting upon said trigger element whereby to hold said element yieldably in normal position and to return it to that position, and initially rocking it during the return actuation whereby to engage the extension 35 thereof with said hammer retaining element to release the hammer therefrom.

In testimony whereof I have signed my name to this specification.

JOHN D. POLLARD.
